UNITED STATES PATENT OFFICE

WILLIAM H. APPLEGATE, OF PHILADELPHIA, PENNSYLVANIA

WRENCH

Application filed September 17, 1930. Serial No. 482,436.

My invention relates to new and useful improvements in a wrench and has for one of its objects to provide a quick-acting wrench which may be readily moved into engagement with or disengaged from the work.

Another object of the invention is to so construct the wrench that it may be held in and operated by one hand while adjusting the same in connection with smaller or larger work than that with which it had been just previously used.

A further object of the invention is to provide a unique construction and arrangement of inner jaw whereby it will be caused to firmly grip the work when the wrench is turned in one direction and released from said work when moved in the opposite direction without changing the adjustment.

A still further object of my invention is to construct a quick acting device for use distinctly as a pipe or nut wrench.

With these ends in view, this invention consists in the details of construction and combination of elements hereinafter set forth and then specifically designated by the claims.

In order that those skilled in the art to which this invention appertains may understand how to make and use the same, I will describe its construction in detail referring by numerals to the accompanying drawings forming a part of this application, in which:—

Fig. 1 is a side elevation of a wrench constructed in accordance with my invention and showing an inner and movable jaw having a serrated working surface adapting the wrench particularly for use in connection with pipes.

Fig. 2 is a front elevation or edge view thereof with the handle grip removed.

Fig. 3 is a rear elevation or edge view of the same.

Fig. 3a is a side elevation similar to Fig. 1 on a smaller scale showing a plain inner jaw, the working surface of which is substantially parallel to the working face of the outer or stationary jaw adapting the wrench for use in connection with nuts or similar irregular shaped objects.

Fig. 4 is an enlarged fragmentary longitudinal sectional view.

Fig. 5 is an upper end view of the yoke or inner jaw carrier.

Fig. 6 is a longitudinal sectional view thereof on the line 6—6 of Fig. 5.

Fig. 7 is a side elevation of the inner or movable jaw shown in Figs. 1 and 4.

Fig. 8 is a lower or inner end view of the inner or movable jaw.

Fig. 9 is a side elevation of the ratchet rack per se.

Fig. 10 is a face view thereof.

Fig. 11 is a side elevation of the pawl.

Fig. 12 is an inner end view thereof.

In carrying out my invention as herein embodied, 15 represents the outer or stationary jaw formed with the shank 16 terminating in a stem 17, the cross sectional area of which is smaller than that of the shank providing a shoulder 18 against which may rest a ferrule 19 or equivalent, surrounding or covering the inner end of the grip or hand hold 20 which is mounted on the stem and held in place by a suitable fastening 21, such as a nut, threaded on the terminal of the stem which is provided with threads 22 for such purpose.

If found desirable, a ferrule 23 or equivalent may be interposed between the fastening means 21 and the outer end of the hand hold or grip 20.

The working face of the outer or stationary jaw is serrated, as indicated at 24, and said serration may be formed directly and upon said jaw or upon an insert 25 set into the jaw from the working face.

The shank 16 has a longitudinal groove 26 formed in its forward face and running from the lower or inner end of said shank to a point adjacent the stationary jaw 15 and a recess 27 is formed in the lower part of said shank adjacent its inner end from the back forwardly with at least one part of it passing all the way through as indicated at 28, leaving a supporting wall 29 to which is fastened one end of a plate spring 30, the opposite or free end of said spring bearing against the tail 31 of the pawl 32 which is pivoted intermediate its ends as at 33 within the recess 27 and the nose of said pawl has a number of ratchet teeth 34 for registration.

or engagement with the ratchet teeth 35 on the ratchet rack bar 36.

The ratchet rack bar 36 is adapted to work in the groove 26 when moving with the yoke 5 or inner jaw carrier 37 comprising particularly an enlarged portion or body 38 with a socket 39 therein and a smaller depending portion or leg 40 and the ends of said rack bar are bent outward and engage the upper 10 and lower ends of the inner jaw carrier. The said inner jaw carrier or yoke also includes a strap 41 which completely encircles the shank 16 and a two-piece strap 42, the parts of which are spaced apart at the back 15 of the wrench shank to permit movement or operation of the pawl 32.

Within the socket 39 is pivotally mounted an inner jaw 43, Figs. 1, 4 and 7 or an inner jaw 44, Fig. 3a. The inner jaw 43 includes 20 a neck 45 and a head 46 with an inclined serrated working face 47, the inclination being from the forward end of the jaw upwardly and inwardly toward the shank and stationary jaw of the wrench and said inner 25 jaw is normally forced away from the wrench shank by a plate spring 48 fixed to the shank and engaging a wall of the body of the inner jaw carrier or yoke within the socket 39.

The jaw 44 also includes a neck 49 and 30 head 50, the working face of which is preferably smooth or plain and substantially parallel with the working face of the outer or stationary jaw and like the inner jaw 43 is pivoted within the socket 39 in the body of 35 the inner jaw carrier or yoke and may be provided with the spring 48 if desirable although this is not essential and is preferably eliminated. Either of these jaws may be used and are therefore interchangeable with 40 each other being only necessary to remove the pivot pin 51 to permit the removal of one jaw and the substitution of the other.

In practice, by pressing inward upon the tail end 31 of the pawl 32 against the action 45 of the spring 30, the teeth of said pawl will be disengaged from the ratchet rack bar 36 permitting the inner jaw carrier or yoke with the inner jaw to slide back or downward providing the wrench is held with the stationary 50 jaw rest above the handle. As the inner jaw and component parts reach approximately the position desired, the pawl 32 is released and the spring 30 will move it into engagement with the ratchet rack bar. The wrench 55 may then be placed upon the work and the inner jaw carrier or yoke together with the inner jaw can be moved along the shank 16 by use of the operator's thumb against the outer or lower end of the inner jaw carrier 60 until the inner jaw engages the work, it being understood, of course, that the outer jaw is already in engagement with the work. Thereafter, the wrench may be used in the usual way and as soon as the operations are 65 completed, the pawl is again disengaged from

the ratchet rack bar which will release the inner jaw, the same either dropping back by gravity or the operator holding the inner jaw in engagement with the work and moving the outer jaw away.

Of course I do not wish to be limited to the exact details of construction as here shown, as these may be varied within the limits of the appended claim without departing from the spirit of my invention.

Having thus fully described my invention, what I claim as new and useful is:—

In a wrench, the combination of an outer jaw, a shank formed with said jaw and having a longitudinal groove in its forward face and also provided with a recess in the back adjacent the end opposite said jaw, said recess having a portion extending through the shank for communication with the groove, a spring actuated pawl pivoted within the recess with its nose projecting into the groove and its tail extending outside of the shank at the back thereof, an inner jaw carrier provided with a tapered socket, the larger end of which is nearest the outer jaw, a strap at the socketed end of said inner jaw carrier completely surrounding the shank, a two piece strap at the opposite end of said inner jaw carrier and partially surrounding the shank with the adjacent ends of the two pieces spaced apart at the back of the shank to permit movement of said two piece strap past the projecting tail of the pawl, said straps slidably mounting said inner jaw carrier on the shank, a separate ratchet rack bar inserted in the carrier prior to the latter being placed upon the shank, the ends of said rack bar engaging the ends of the carrier to prevent longitudinal movement of said bar relative to the carrier and said bar being housed within the groove in the shank after the carrier has been placed on said shank, and a separate inner jaw provided with a neck which is pivoted within the socket of the carrier, said inner jaw being spring actuated in one direction.

In testimony whereof, I have hereunto affixed my signature:

WILLIAM H. APPLEGATE.
